UNITED STATES PATENT OFFICE.

LOYD R. STOWE, OF MAPLEWOOD, MISSOURI.

AUTOMATIC STOKER.

Application filed June 18, 1919. Serial No. 304,534.

To all whom it may concern:

Be it known that I, LOYD R. STOWE, a citizen of the United States, residing at Maplewood, in the county of St. Louis and State 5 of Missouri, have invented certain new and useful Improvements in Automatic Stokers, of which the following is a specification.

This invention relates to improvements in stokers, and its purpose is to provide an improved automatic stoking device in which the under-feed principle is combined with means for securing a positive feed of the fuel throughout the length of the grate.

It is well known that in the ordinary under-feed stoker, it is impossible to secure a uniform and positive movement of fuel toward the discharge end of the grate or to secure and maintain a uniform condition of the fuel bed, especially when thin fires are being carried. It is well known that in the usual type of under-feed stoker a large quantity of fuel containing high percentages of combustibles reach the discharge end of the stoker, where, for the sake of economy, it must be held until the combustion is nearly completed, while other parts of the fuel reach the discharge end of the grate quite well consumed, and for the purpose of avoiding clinkers these other parts must be immediately discharged to the ash pit. The difficulty caused by this irregularity is increased by the absence in the usual under-feed stoker of a positive and continuous means of discharging the refuse. These defects in the under-feed stoker have been overcome in the present invention by combining a plurality of under-feed devices with a plurality of grate chains which are arranged in alternation, so that the fuel which is moved upwardly by the under-feed devices is positively moved along the grate by the moving chains, thereby securing a positive feed of the fuel from one end of the grate to the other and a positive discharge of the ash at the lower end of the grate. By means of the present invention, it is possible to adjust the movements of the under-feed devices and the moving chains in order to secure any desired depth and condition 50 of the fuel over any part of the grate surface.

The nature of the invention and the various objects to be attained thereby will be understood from the following specification, taken in connection with the accompanying

drawings, in which one embodiment is illustrated.

In the drawings—

Figure 1 shows a top plan view of my improved stoker, parts of the same being removed for the sake of clearness;

Fig. 2 shows an end elevation of the forward end of the stoker, parts of the same being removed.

Fig. 3 shows a side elevation of the stoker;

Fig. 4 shows a longitudinal sectional view on the line 4—4 of Fig. 1;

Fig. 5 shows a partial transverse sectional view on the line 5—5 of Fig. 3; and

Fig. 6 shows a partial transverse sectional view on the line 6—6 of Fig. 3.

The mechanism of the stoker is supported on a foundation 10 of concrete or the like which is preferably arranged in a series of steps 10^a, 10^b, and 10^c. A conduit 11 is provided between the two upper steps of the foundation, and a blast of air under pressure is supplied through this conduit to the underside of the grate, the flow of air being regulated by a valve 12. The stoker comprises a pair of side frames 14 which are provided with upper and lower parts 14^a, 14^b and 14^c, respectively, adapted to rest upon the steps 10^a, 10^b and 10^c of the foundation. One or more intermediate center frames 15 are located between the side frames 14 and each center frame is provided with parts 15^a, 15^b and 15^c which rest upon the parts 10^a, 10^b, and 10^c, respectively, of the foundation.

The side frames and the center frame carry the fuel feeding mechanism which comprises a plurality of under-feed retorts 16 which extend downwardly substantially throughout two-thirds of the length of the grate and which are arranged in alternation with a plurality of endless flexible grate chains 17 extending throughout the length of the grate. A plurality of other flexible chains 18 are mounted between the chains 17 from the lower ends of the under-feed retorts 16 to the discharge end of the grate, and the lower portions of the chains 17 and the chains 18 have a lesser inclination to the horizontal than the fuel retorts and the upper parts of the chain 17, as shown particularly in Fig. 4. The lower ends of the side frames and the center frame have their upper parts constructed to conform to the con-

formation of the upper surface of the grate. The inclination of the upper portion of the grate surface preferably approximates the angle of repose, but it is found in practice 5 that an angle of about 20° is a suitable angle of inclination for most fuels, and the decreased inclination of the lower part of the grate surface is provided in order to effect a retardation of the fuel adjacent the lower 10 end of the grate.

The fuel retorts 16 comprise metal troughs 20 which are rectangular in cross-section, as shown in Fig. 5, and tapered toward their lower ends, so that the depth of 15 each trough gradually decreases toward the lower end of the grate. These troughs are supported at their upper ends on a transverse I-beam 21 which has its ends secured to the side frames 14 by means of angle 20 plates 22. The I-beam 21 is supported between its ends by one or more posts 23 which rest directly on the foundation 10^a. The lower portions of the troughs 20 are supported by transverse I-beams 24 which 25 are secured to the upper side of the center frame 15 and to the inner walls of the side frames 14, the lower parts of the troughs being provided with downwardly extending portions 20^a which are secured to the lower 30 I-beam 25. The upper end of each trough is provided with a top wall 20^b which cooperates with the side walls and the lower wall of the trough to form a guideway for a fuel pusher or ram 27. These pushers reciprocate in their guides to push the fuel 35 downwardly onto the grate surface and they are operated by connecting rods 28 which are detachably connected through bearing blocks 29 with the cranks 30^a of a crank 40 shaft 30 journalled in bearings 31 carried by the troughs 20 and in bearings 32 carried by the side frames 14. The alternate cranks 30^a of the crank shaft are directed 45 in opposite directions, so that one of the pushers 27 is in its uppermost position when the next adjacent pistons are in their lower positions.

The crank shaft 30 extends through one 50 of the side frames 14, and has its outer end journalled in a bearing 33 carried by an auxiliary frame 34 which is secured to the side frame. A gear 35 is secured to the shaft 30 between the side frame and the bearing 33, and this gear is adapted to mesh with a pinion 36 secured to an intermediate shaft 37. The shaft 37 also has fixed thereon a gear 38 which meshes with a driving pinion 39 secured to the shaft 40 journalled in bearings 45 carried by the upper parts of the side frame and the auxiliary frame 34. The shaft 40 is driven by a ratchet wheel 41 which is fixed thereon and adapted to be engaged by a pawl 42 pivoted on the bell crank 43 which has its other arm 43^a connected to an operating rod 44. The rod 44 may be reciprocated

by any desired mechanism in order to effect the rotation of the ratchet wheel and the consequent rotation of the crank shaft 30 which causes the pushers 27 to reciprocate 70 in their guides.

The fuel to be burned is fed to the grate from a hopper 45 which comprises an inclined lower wall 46 and a vertically movable feed gate 47 by which the size of the outlet opening 48 may be controlled. The 75 furnace arch 49 of fire brick or the like extends upwardly and rearwardly from the feed gate 47, and the space between the lower wall 46 of the hopper and the foundation 10 is closed across the front end of the furnace by a front wall 50 of sheet metal, or the like, which may be provided with a plurality of openings to permit access therethrough to the operating mechanism of the stoker. The fuel which passes through the outlet opening 48 drops into the retorts formed 80 by the troughs 20, and the pushers 27 engage the fuel and push it downwardly in the inclined troughs, so that it is gradually forced upwardly onto the fuel bed beneath the burning fuel. As the fuel rises above the upper edges of the side walls of the troughs it passes thereover onto the chains 17, each of which is formed of a plurality of series 85 17^a of alining links 51. The links in one series overlap those in the adjacent series, and connecting pins 52 extend transversely therethrough to form a pivotal connection between the links of the chain. Portions 90 of the innermost links of each chain are cut away on their inner sides, as shown at 53, to receive sprocket wheels adapted to engage the pivot pins or connected parts for advancing the endless grate chains and all of 95 the links are provided with grooves in their sides to form apertures for permitting the flow of air to the fuel. The form of grate chain herein shown together with means to 100 vary the tension thereof is more fully illustrated and described in my United States 105 Patent No. 1,379,135 granted May 24, 1921. 110

At the upper end of the grate, the chains 17 are mounted on idler wheels 55 which are located between the fuel retorts and adapted 115 to rotate on the crank shaft 30 between fixed collars 56. At the lower end of the grate, the chains 17 extend around sprocket gears 58 which are secured to a drive shaft 60 extending transversely of the furnace and mounted in bearings 61 carried by the side frame and a bearing 62 carried by the lower portion of the center frame 15. The bearing 62 is open on its upper side and is provided with a slot 63 to permit the insertion 120 of the shaft. The chains 17 also pass over chain supporting wheels 64 mounted on a shaft 65 which is supported by bearings 66 carried by the side frame and by a bearing 67 carried by the center frame, the bearing 67 being open on its upper side to permit the 125 130

insertion of the shaft. The shaft 65 carries a plurality of other chain supporting wheels 69 which are located beneath the lower ends of the troughs 20 and the lower driving shaft 50 carries a plurality of fixed sprocket gears 70 which are in alinement with the wheels 69. The short flexible chains 18 which extend from the fuel retorts to the lower end of the grate are mounted on the wheels 69 and sprocket gears 70 and are formed of complementary links which are connected together in the manner that the links of the chain 17 are connected. The space below the lower end of the middle fuel retort which 15 is located above the center frame 15 is preferably occupied by two chains 18 which are spaced apart, and the lower part 15^a of the center frame extends upwardly between these chains with the upper surface thereof 20 in alinement with the grate surface formed by the upper surfaces of the links. The upper and lower stretches of the chains 17 and 18 are supported by tubular rollers 72 which are adapted to rotate on rods 73 extending 25 between the side frames and the center frame 15. These rods are detachably carried by the frame members and may be secured in position by nuts 74 or by other suitable means which will permit the ready removal 30 of said rods. The upper stretches of the chain 17 are supported between the fuel retorts by flanges 75 which are formed integrally with the lateral walls of the troughs and extend transversely thereto.

35 Both the chains 17 and the chains 18 are driven by the lower shaft 60, which has a worm-wheel 76 secured to the end thereof, and this worm wheel is engaged by a worm 77 which is secured to the lower end of a 40 shaft 78 journalled in bearings 79 secured to the side frame 14. The shaft 78 extends upwardly to the forward end of the stoker where it is journalled in a bracket 80 secured to the forward end of the side frame. A 45 ratchet wheel 81 is secured to the shaft 78 between the arms of the bracket 80, and this ratchet wheel is adapted to be driven by a pawl 82 which is pivoted on one arm of a bell crank lever 83, the other arm of this 50 lever being pivotally connected to an operating rod 84 which may be reciprocated by any desired mechanism in order to operate the drive shaft 60 and thereby actuate the chains.

55 In the operation of the stoker, the feed gate 47 may be located in any desired position in order to adjust the relative action of the under-feed mechanism and the flexible chains in advancing the fuel over the grate. When raised substantially above the 60 grate surface, the gate 47 permits the coal to fall onto the chains as well as into the troughs, so that some fuel is carried downwardly onto the grate by the advancing chains, and an additional quantity of fuel is 65 fed onto the grate by the downward move-

ments of the pushers 27. The positive feed of the chains is thus combined with the operation of the under-feed mechanism, so that a greater uniformity in the thickness of the entire fuel bed is maintained, while at the same 70 time an adequate air supply is provided through the air spaces of the chains. The front wall 50 confines the air blast at the forward end of the stoker and a sheet metal partition is also preferably provided across 75 the ends of the side frames beneath the lower end of the grate in order to separate the air chamber from the ash pit. The chains carry the fuel positively from the upper part of the grate to the ash pit, and the lesser inclination of the lower part of the grate operates to retard the fuel and to effect a thickening of the fuel bed adjacent the bridge wall, so that the burning out of the fuel bed at the lower end of the grate is prevented 80 without interfering with a positive discharge of the ash. If the feed gate 47 be lowered until it rests directly on the upper parts of the fuel troughs, the feeding action of the chains in conveying fuel directly from the 85 fuel hopper is eliminated, and the fuel is fed to the grate by the under-feed mechanism alone after which the chains cooperate with the pistons to advance the fuel downwardly throughout the grate surface. The action 90 of the stoker can be regulated by adjusting the speed of the ratchet mechanism by which the chains are operated and by adjusting the ratchet mechanism by which the under-feed mechanism is operated. If the chains 95 run relatively slow there will be a greater accumulation of ash on the lower stretches of the chains, and the thickness of the fuel bed at the lower end of the grate will be increased. The use of one or more center 100 frames 15 makes it possible to increase the width of the stoker to any desired extent while at the same time providing the necessary support for the intermediate parts of 105 the grate.

110 Although I have shown and described one embodiment of the invention for purposes of illustration, it will be understood that it may be constructed in various other forms without departing from the scope of the 115 appended claims.

What I claim is:

1. The combination in a stoker of spaced grate chains inclined downwardly at their forward portions, feeding troughs, pusher members coacting therewith, said troughs being mounted between said spaced chains and having the sides thereof tapered to accord with the inclination of said chains, and substantially horizontal endless chains located at the extremity of each of said troughs between said first named chains adapted to retard the movement of the fuel at the forward end of the stoker. 120
2. The combination in a stoker of a pair 125

of side frames, a fuel trough mounted between said side frames, endless grate chains mounted on opposite sides of said fuel trough, a crank shaft journalled in said side frames, a pusher mounted in said fuel trough, means for operatively connecting said pusher with said crank shaft, a second shaft mounted parallel to said crank shaft, a series of sprocket gears fixed on said second shaft, a plurality of chain supporting wheels rotatably mounted on said crank shaft, said grate chains being mounted on said sprocket gears, and said chain supporting wheels, and means for actuating each of said shafts.

3. The combination in a stoker of a pair of side frames, a fuel trough mounted between said side frames and extending through a portion of the length of the grate, an endless grate chain extending in alignment with said fuel trough through the re-

maining portion of the length of the grate, a shaft journalled in said side frames adjacent the feeding end of the grate, means actuated by said shaft for advancing fuel in said trough, a second shaft journalled in said side frames adjacent the lower end of said trough, a third shaft journalled in said frames adjacent the lower end thereof, wheels mounted on said second shaft and sprocket gears on said third shaft for supporting said endless grate chain, other wheels mounted on said first-named shaft and other sprocket gears on said third shaft, other grate chains extending throughout the length of the grate on opposite sides of said fuel trough and supported by said other wheels and sprocket gears, and means for driving said third shaft.

In testimony whereof, I have subscribed my name.

LOYD R. STOWE.
